UNITED STATES PATENT OFFICE.

ALBERT S. WILKINSON, OF PAWTUCKET, RHODE ISLAND.

IMPROVEMENT IN HORSESHOES.

Specification forming part of Letters Patent No. **56,309**, dated July 10, 1866.

To all whom it may concern:

Be it known that I, ALBERT S. WILKINSON, of Pawtucket, Providence county, State of Rhode Island, have invented a new and Improved Racing-Horseshoe; and I do hereby declare that the following is a full, clear, and exact description thereof, which will enable others skilled in the art to make and use the same, reference being had to the accompanying drawings, forming part of this specification, in which—

Figure 1, Sheet 1, is a top view of my improved racing-horseshoe. Fig. 2 is vertical section through the line *xx* in Fig. 1. Fig. 3 is a rear view of the same.

Similar letters of reference in the different figures denote corresponding parts.

The ordinary racing-shoe is made very light, narrow, and thin; but although so lightly constructed, when it is nailed to the hoof by nine nails, as is commonly done, it confines the foot and destroys the elasticity or natural spreading of the rear portion of the same under pressure.

The object of this invention is to overcome this objection by producing a shoe which can be attached to the foot in a reliable manner with a less number of nails, or in such manner as to allow nail-fastenings to be altogether dispensed with, thereby giving an ease and elasticity to the foot not attainable in racing-shoes of ordinary construction.

My improved racing-shoe consists in a very light steel shoe having a continuous clip running around the shoe, which gives it great vertical stiffness and more thoroughly protects the edge of the hoof; and the said continuous clip being more elevated at the toe and heel, and the whole clip being of such shape as to fit over the shelving edge of the hoof, but little fastening at the heel of the shoe is all that is required to hold it securely; and when the shoe is sprung on this heel-fastening may consist of a single nail or screw in each heel, or of a connection made between the tops of the heel-clips; and my invention also consists in slitting the shoe or bottom plate thereof radially near its forward part, so as to allow free lateral expansion to the heel or quarters of the hoof.

Having described the nature of my invention, I will proceed to describe its construction and operation.

A A, Sheet 1, in the accompanying drawings, is the body of the shoe, and B' B b is a continuous clip running entirely around the shoe. This continuous clip is more elevated at the toe, as shown by B', and also at the heel, as shown by b b.

The bed-plate A of the shoe is slitted, as shown by slits *a a*, Fig. 1, so as to weaken the shoe laterally and give lateral elasticity or play to the heels of the shoe. This shoe is made to accurately fit the foot, and is then sprung on and secured at the heel by a single nail, *d*, Fig. 1, placed well back in each heel, the toe of the shoe being held to the foot by the toe-clip alone, or by the toe-clip B' and one or two nails, *c c*, Fig. 1, or by using straps to secure the heel of the shoe, while the toe is held to the hoof by the toe-clip. The shoe may be secured to the foot without the use of nails. When the latter mode of fastening is made use of I attach the heel of the shoe to the foot by straps passing over the coronet of quarters of the foot, and when the heel is so secured the toe of the shoe is held firmly to the hoof by the toe-clip and by the continuous clip, the continuous clip securing the shoe horizontally on the bottom of the foot in every direction.

If the heel-clips *b b* are elevated somewhat, they may be buttoned together or otherwise connected, and still the elasticity of the heel is preserved as long as such heel-connection is made considerably above the plane of the shoe or bed-plate A of the shoe, (see rear view, Fig. 3;) or the tops of the heel-clips may not have a rigid connection, but may be linked together by a strong strap of rubber or other elastic material.

A greater or less number of the slits *a* may be made in the bottom plate of the shoe, as considered most desirable.

By these means a shoe is provided which is light and elastic, and which, with a minimum of weight, gives a greater degree of protection to the foot than such shoes as constructed heretofore.

The spring-joints formed by slitting the

shoe may be applied to any kind of horse-shoe.

Having thus described my invention, what I claim as new, and desire to secure by Letters Patent, is—

A continuous clip, B B' b, constructed as described, in combination with the notched bar A, the whole being constructed and oper-

ated substantially in the manner and for the purpose set forth.

ALBERT S. WILKINSON.
